UNITED STATES PATENT OFFICE.

ROBERT G. PILKINGTON, OF CHICAGO, ILLINOIS, ASSIGNOR TO DODGE MANUFACTURING COMPANY, OF MISHAWAKA, INDIANA, A CORPORATION OF INDIANA.

DESIGN FOR A PACKAGE-DELIVERY-CAR BODY.

53,400.

Specification for Design.

Patented June 3, 1919.

Application filed February 23, 1917. Serial No. 150,585. Term of patent 14 years.

To all whom it may concern:

Be it known that I, ROBERT G. PILKINGTON, a citizen of the United States, residing at Chicago, in the county of Cook and State of Illinois, have invented a new, original, and ornamental Design for a Package-Delivery-Car Body, of which the following is a specification, reference being made to the accompanying drawing, forming part thereof.

Figure 1 is a right-hand side elevation of

a package delivery car body showing my new design.

Fig. 2 is a left-hand side elevation.

Fig. 3 is a front elevation.

I claim:

The ornamental design for a package delivery car body, as shown.

ROBERT G. PILKINGTON.

Witnesses:

A. L. AMSTUTZ,

M. S. AMSTUTZ.
